E. F. HATHAWAY

TUBE FRAME

Filed Sept. 1, 1923

Fig. 5.

Inventor:
Edgar F. Hathaway
by
Yes. N. Goddard, atty.

UNITED STATES PATENT OFFICE.

EDGAR F. HATHAWAY, OF WELLESLEY, MASSACHUSETTS, ASSIGNOR TO SHAWMUT ENGINEERING COMPANY, OF BOSTON, MASSACHUSETTS, A CORPORATION OF MASSACHUSETTS.

TUBE FRAME.

Application filed September 1, 1923. Serial No. 660,528.

To all whom it may concern:

Be it known that I, EDGAR F. HATHAWAY, a citizen of the United States, and resident of Wellesley, in the county of Norfolk and 5 State of Massachusetts, have invented certain new and useful Improvements in Tube Frames, of which the following is a specification.

This invention relates to tube frames such 10 as are commonly used in tuft weaving for the manufacture of Axminster carpets or similar pile fabrics, and is intended to provide a construction of tube frame which shall possess a high degree of rigidity and 15 firmness so as to avoid buckling of the frame when the yarn tufts are presented to the fabric being woven without unduly increasing the weight of the tube frame construction.

20 The improvement particularly relates to the construction of the carrier bar which forms the backbone of the whole tube frame and, generally speaking, comprises a tubular or hollow bar through whose middle portion 25 is extended longitudinal reenforcing means formed in a transversely bowed or arch construction so as to engage the internal faces of opposite walls of the carrier bar and support transverse stresses to which the 30 bar is subjected when in use. These and other features of the invention will be particularly explained in the following specification and will be defined in the claims hereto annexed.

35 In the accompanying drawings I have illustrated several forms of construction embodying the principles of the present invention, in which:

40 Figure 1 is a front elevation illustrating a complete tube frame with the middle portion of the carrier bar cut away to expose the interior reenforcing means.

Figure 2 is a transverse section of the same on an enlarged scale.

45 Figure 3 is a transverse section showing a modified construction of reenforcing means.

50 Figures 4 and 5 are transverse sections showing other modifications of stiffening and reenforcing construction.

In the practice of this invention, according to the illustration in Figures 1 and 2 of the drawings, the tube frame comprises a hollow carrier bar 1, of substantially rec-

tangular cross section provided with suspension hangers 2, of any suitable type at its opposite ends for suspending the tube frame from a suitable carrier chain or conveyor, and affording also bearings for the extreme end journals of the yarn-carrier 60 spool 3.

On the front face of the carrier bar is secured a U-shaped attaching strip or channel bar 5, through whose parallel wings the individual tuft tubes 4 are inserted, according to present known practice. The U-shaped tube-attaching bar is firmly but detachably secured against the front face of the carrier bar by means of transverse bolts 8, engaged with tapered fastening nuts 9, 70 which are provided with thin flanges 10, to prevent their passing through the openings provided at intervals for the insertion of the nuts to engage the ends of the transverse bolts.

The reenforcing member shown in Figures 1 and 2 comprises a transverse arch member in the form of a cylindrical tube 6, bowed or bent out of a flat strip of metal with their parallel longitudinal edges very 80 slightly spaced apart so as to permit a slight compression when the reenforcing member is inserted inside the carrier bar so as to establish firm contact or engagement with the opposite walls of the carrier bar.

The bolts 7 which are used to secure the feet of the intermediate spool brackets 3^a, firmly to the top face of the carrier bar may be passed directly through this tubular reenforcing member as shown in Figure 2 so 90 that they do not interfere with the proper bearing or engagement of the reenforcing member with the interior faces of the walls of the carrier bar.

As shown in Figure 3, however, these spool brackets 3^a may be secured to the upper wall of the tubular carrier bar 3^b, and approximately semi-cylindrical reenforcing members 11 may be employed to stiffen the carrier bar. In this case, the reenforcing members 11, are so proportioned that their intermediate portions engage back to back to mutually sustain each other while the end edges of the respective transversely arcuate members engage the opposite walls of the tubular carrier bar. In this instance the curved or transversely arcuate reenforcing members are shown with their four longi-

tudinal edges engaging the opposite walls of the carrier bar at their corners so as to reinforce in all directions.

Still another modified form is shown in Figure 4 which is similar in principle to that shown in Figure 3, only in this case the bearing-like reenforcing members 12, are shown as having polygonal cross section with their outer edges, in each case, engaging adjacent faces of the carrier bar at each of the four corners. In this case also the transverse attaching bolts 7 and 8 may be passed directly through the interposed portions of the reenforcing means. It is immaterial, so far as either of these double reenforcing members are concerned, whether, at their points of contact with each other, the members are spot-welded together or simply form mechanical engagement or contact with each other.

In Figure 5 I have shown the trough-like or transversely bowed reenforcing member in the form of a V-shaped trough 13, having a flanged extension 14 on one side through which are passed the tube-attaching bolts 8.

By reason of the trough-like or transversely arched shape given to each form of reenforcing members, they may be made of comparatively light or thin stock so as not to add materially to the weight of the tube frame particularly as they need not be carried through the entire length of the carrier bar but will suffice to perform their function if extended through the middle portion of the length of the carrier bar as shown. Inasmuch as the transverse bolts, either for attaching the spool-bearing brackets or the tuft tube-attaching member, may pass directly through the reenforcing it will be seen that longitudinal displacement of the shorter reenforcing member is positively prevented.

What I claim is:

1. In a tube frame for supporting the yarn spool and a series of tuft tubes in cooperative relation, the combination of a longitudinal tubular carrier bar and transversely arched reenforcing means disposed interiorly thereof to extend through the middle portion of the length of the bar and having internal bracing engagement therewith, substantially as described.

2. In a tube frame for supporting the yarn spool and a series of tuft tubes in cooperative relation, the combination of a tubular carrier bar of polygonal cross section and interior reenforcing means extend-

ing longitudinally through the middle portion of the bar, said reenforcing means being transversely bowed to form transversely arched means engaging the opposite interior walls of the carrier bar in position to resist transverse stresses on said bar, substantially as described.

3. In a tube frame for supporting the yarn spool and a series of tuft tubes in cooperative relation, the combination of a longitudinal tubular carrier bar, of plural reenforcing members, each being transversely arched and arranged with the lateral edges of their respective arches forming the supporting contact with opposite walls of the bar, said reenforcing means having their intermediate portions arranged back to back to reinforce each other against transverse strains, substantially as described.

4. In a tube frame for supporting the yarn spool and a series of tuft tubes in cooperative relation, the combination with a longitudinal tubular carrier bar of approximately rectangular cross section, and interior reenforcing means extending longitudinally through the middle portion of the bar and arranged to have supporting engagement with the top and bottom and side walls of said bar, substantially as described.

5. In a tube frame for supporting the yarn spool and a series of tuft tubes in cooperative relation, the combination of a hollow longitudinal carrier bar, tuft tube-attaching bolts passed at intervals transversely through said bar, and longitudinal reenforcing means extending through the middle portion of said bar and arranged to form supporting engagement with opposite walls of said bar, said reenforcing means being penetrated by said fastening bolts, substantially as described.

6. In a tube frame for supporting the yarn spool and a series of tuft tubes in cooperative relation, the combination of a longitudinal tubular carrier bar, interior trough-like reenforcing means arranged to engage opposite walls of said bar and support them against transverse strains, said reenforcing means extending through the middle portion of said bar, and means for preventing the longitudinal displacement of said supporting means, substantially as described.

In witness whereof, I have subscribed the above specification.

EDGAR F. HATHAWAY.
